UNITED STATES PATENT OFFICE

2,288,383

RAILWAY TRUCK

Robert G. Anderson, Erie, Pa., assignor to General
Electric Company, a corporation of New York

Application October 30, 1940, Serial No. 363,414

8 Claims. (Cl. 105—185)

My invention relates to trucks for railway vehicles.

An object of my invention is to provide an improved resilient support and restraint device for a railway truck bolster.

Another object of my invention is to provide an improved railway truck having a resilient cushion support for a laterally movable bolster adapted to restrain lateral movement of the bolster and a tilting restraint device for restraining relative tilting between the bolster and the truck.

A further object of my invention is to provide an improved tilting restraint device for a railway truck bolster which is adapted to provide a tilting lateral pendulum motion to the bolster about a predetermined center to restrain such motion.

Further objects and advantages of my invention will become apparent and my invention will be better understood from the following description referring to the accompanying drawings, and the features of novelty which characterize my invention will be pointed out with particularity in the claims annexed to and forming part of this specification.

In the drawings, Fig. 1 is a plan view, partly broken away, of a railway truck illustrating an embodiment of my invention; Fig. 2 is a side elevational view of the truck shown in Fig. 1 partly broken away to illustrate the relative supporting arrangement of the truck frame on the journal boxes; Fig. 3 is a sectional view taken along line 3—3 of Fig. 1; and Fig. 4 is a plan view of a railway truck embodying another modification of my invention.

Referring to the drawings, I have shown a truck for a railway vehicle provided with a pair of axles 10 supported by wheels 11 and having journal bearing boxes 12 arranged on each end thereof. A truck side frame 13 is arranged on each side of the truck, and the adjacent ends of these side frames on opposite sides of the truck are connected together by end frames 14. A pair of spaced apart transversely extending cross ties or transoms 15 is arranged intermediate the ends of the truck between the two side frames 13 and is rigidly supported thereon on bearing surfaces 16 and 17, more clearly shown in Figs. 2 and 3. The side frames are resiliently supported by coil springs 18 which engage spring seats 19 formed on the side frames 13 and spring seats 20 formed on the journal boxes 12. One of these springs 18 is arranged on each side of each journal box 12 so that a substantially balanced load is transmitted to the journal boxes 12 on each side thereof. In order to support the vehicle load upon the truck, a center plate 21 is arranged on a laterally movable bolster 22 which is supported on the truck by resilient fluid cushions 23. These cushions 23 are of a pneumatic type and each is

provided with an upper bolster supporting surface 24 arranged to engage a complementary supporting surface 25 formed on each end of the bolster. The lower side of each cushion engages a longitudinally extending supporting channel member 26 which is rigidly secured to the transoms 15 and is formed as a surge chamber communicating with the interior of the pneumatic cushion 23 through a valve 27. Air is supplied to the supporting channel member 26 by a suitable tubular connection 28 connected to a reservoir which is supplied with air from air supply for the vehicle brakes. As is more clearly illustrated in Figs. 2 and 3, the supporting channel member is arranged to support the pneumatic cushion 23 at an angle to the horizontal inclined inwardly, so that the axes of the two cushions intersect at a point vertically above the center plate 21. With such an arrangement, relative lateral movement of the bolster 22 with respect to the truck frame will be resisted by the distortion of the pneumatic cushion 23, and the angular tilted arrangement of the two cushions will tend to center the bolster by a gravity reaction as relative lateral displacement of the bolster with respect to the truck frame will tend to cause the bolster to rise as it distorts the cushions 23. A pair of guard plates 29 is secured to the transoms 15 in spaced apart relation above complementary guard flanges 30 secured to the bolster 22 in order to limit the relative vertical movement of the bolster with respect to the truck frame.

In order to prevent or limit tilting of the bolster 22 with respect to the truck frame, I provide a tilting restraint device which includes transversely extending torsion rods 31 journaled in bearings 32 secured to the transoms 15 by clamps 33. A pair of longitudinally extending link members 34 is arranged adjacent each end of the bolster 22, and each of the link arms 34 is connected to the bolster by a universal ball and socket joint 35 which is pivotally mounted on the bolster by a pivot pin 36 which extends through the ball of the joint 35 and is journaled in bearing blocks 37. These bearing blocks are mounted in a supporting bracket 38, and one set of bearing blocks at each end of the bolster 22 is adapted to slide longitudinally in its mountings to provide for relative longitudinal displacement between the supporting bracket 38 and the adjacent ends of the torsion rods 31. The link arms 34 are formed with clevises 39 at their outer ends and are pivotally secured to the adjacent ends of the torsion rods 31 by knuckle pins 40 having axes which extend substantially transversely of the torsion rods 31 at an acute angle to the longitudinal axis of the torque rods 31 as shown in Figs. 1 and 3 tending to provide a tilting lateral pendulum motion to the bolster

about a predetermined center vertically above the longitudinal center line of the truck. This tends to cause the vehicle body supported on the center plate 21 to have a pendulum motion about a longitudinal center line through the vehicle body, thereby tending to restrain relative movement of the vehicle with respect to the truck. Furthermore, relative tilting of the bolster 22 with respect to the truck frame causes one end of the bolster to rise and the other end to fall below normal level position, thereby transmitting substantially equal and opposite torsional forces to the ends of the torsion rods 31 which tend to cause the raised end of the bolster to move downwardly and the lowered end of the bolster to move upwardly, thereby restraining the tilting of the bolster.

In Fig. 4, I have shown a modification of the construction shown in Figs. 1 and 3 wherein the railway truck axles, wheels, frame, bolster, and bolster supports are substantially the same as those shown in Figs. 1 to 3, inclusive. This modified construction is provided with a tilting restraint device which includes a torsion spring rod 31 secured to one of the transoms or cross ties 15 by clamping straps 33. In order to restrain tilting of the bolster 22 with respect to the truck frame, a link arm 34 is pivotally secured to the bolster adjacent each end thereof by a universal ball and socket joint 41. These ball and socket joints are pivotally secured to the ends of the bolster 22 through equalizing arms 42 which are pivotally mounted on the bolster by pivot pins 43. The outer end of each of the link arms 34 is formed as a clevis 39 which is pivotally secured to an end of the torsion rod 31 by a knuckle pin 40 the axis of which extends substantially transversely of the torsion rod and slightly at an angle to the longitudinal axis thereof as in the construction shown in Fig. 1. Another link arm member 44 is pivotally secured to the other end of each of the equalizing arms 42 by a universal ball and socket joint 45 and is pivotally secured to the other transom 15 by a ball and socket joint 46. A pair of arms 34 and 44 extends substantially longitudinally of the truck frame and transversely of the bolster 22 at each end thereof, such that when the bolster 22 tends to tilt with respect to the truck frame and one end thereof moves upwardly while the other end thereof moves downwardly, the equalizing arms 42 will pivot about the pivot pins 43 to provide for the change in distance between these pins and the outer ends of the link arms 34 and 44 secured to the torsion rod and to the transom, and the link arms 34 at opposite ends of the torsion rod 31 will transmit a torsional force to the rod 31 acting in opposite directions at opposite ends. The torsional reaction of the rod 31 will produce a resisting force which will be transmitted through the link arms 34 to the bolster and will tend to raise the end thereof which moves downwardly and to lower the end of the bolster which moves upwardly, thereby restraining tilting of the bolster. The link arms 44 will cooperate with the link arms 34 in maintaining the bolster 22 in a longitudinally aligned position with respect to the truck frame, thereby restraining nosing of the truck. With this modified construction, lateral restraint of the bolster 22 to relative lateral movement thereof with respect to the truck frame is provided by the resilient pneumatic fluid cushion supports 23, as in the construction shown in Figs. 1 to 3. These cushions are arranged to support the bolster at

each end thereof on longitudinally extending channel members 26 which are mounted on the transoms 15 of the truck frame. This tilting restraint device construction is somewhat more simple and more readily adaptable to various truck constructions than that shown in Figs. 1 to 3, inclusive, whether or not pneumatic cushions are provided for supporting the ends of the laterally movable bolster on the truck frame.

While I have illustrated and described particular embodiments of my invention, modifications thereof will occur to those skilled in the art. I desire it to be understood, therefore, that my invention is not to be limited to the particular arrangements disclosed, and I intend in the appended claims to cover all modifications which do not depart from the spirit and scope of my invention.

What I claim as new and desire to secure by Letters Patent of the United States:

1. A vehicle truck having a frame including side frames and a pair of transoms extending therebetween, a bolster arranged between said transoms, means for supporting said bolster on said truck frame for relative lateral and vertical movement therebetween, a tilting restraint device including a torque rod mounted on one of said transoms, a pair of arms, means for providing a pivotal connection between one end of one of said arms and an end of said bolster, means for providing a pivotal connection between an end of the other of said arms and the other end of said bolster, and means for connecting the other end of each of said arms to said torque rod with one arm arranged adjacent each end of said rod for pivotal movement about an axis extending substantially transversely of said rod at an angle for providing a tilting lateral pendulum motion centering force to said bolster about a predetermined center.

2. A vehicle truck having a frame including side frames and a pair of transoms extending therebetween, a bolster arranged between said transoms, means including a pneumatic cushion for supporting said bolster on said truck frame, a tilting restraint device including a torque rod mounted on one of said transoms, a pair of arms, means for providing a universal joint connection between one end of one of said arms and an end of said bolster, means for providing a universal joint connection between an end of the other of said arms and the other end of said bolster, said connecting means for at least one of said arms adjacent each end of said bolster being constructed to provide for relative movement longitudinally of said arm between said bolster and said arm, and means for connecting the other end of each of said arms to said torque rod with one arm arranged adjacent each end of said rod for pivotal movement about an axis extending substantially transversely of said rod at an angle for providing a tilting lateral pendulum motion centering force to said bolster about a predetermined center.

3. A vehicle truck having a frame including side frames and a pair of transoms extending therebetween, a bolster arranged between said transoms, resilient means having an axis at an angle to the horizontal for supporting said bolster on said truck frame and providing a gravity centering reaction on said bolster, a tilting restraint device including a torque rod mounted on one of said transoms, a pair of arms, means for providing a universal joint connection between one end of one of said arms and an end

of said bolster, means for providing a universal joint connection between an end of the other of said arms and the other end of said bolster, means for connecting the other end of each of said arms to said torque rod with one arm arranged adjacent each end of said rod for pivotal movement about an axis extending substantially transversely of said rod at an angle for providing a tilting lateral pendulum motion centering force to said bolster about a predetermined center, and means associated with certain of said connections for providing for a change in distance between the ends of said torque rod and the ends of said bolster on relative movement therebetween without restraint thereto by said arms.

4. A vehicle truck having a frame including side frames and a pair of transoms extending therebetween, a bolster arranged between said transoms, means for supporting said bolster on said truck frame, a tilting restraint device including pairs of arms extending in opposite directions substantially transversely of said bolster arranged one pair adjacent each end of said bolster, means for providing universal joint connections between said bolster and the end of each of said arms adjacent said bolster, a torque rod mounted on one of said transoms, means for securing the other ends of said arms extending from opposite ends of said bolster on one side thereof to one of said torque rods with one arm secured to said rod adjacent each end thereof for pivotal movement about an axis extending substantially transversely of said rod, said connecting means for at least one of said arms adjacent each end of said bolster being constructed to provide for relative movement between said bolster and said arm, and means for connecting the other ends of said arms extending from opposite ends of said bolster on the other side thereof to said frame for universal movement with respect thereto.

5. A vehicle truck having a frame including side frames and a pair of transoms extending therebetween, a bolster arranged between said transoms, means for supporting said bolster on said truck frame, a tilting restraint device including pairs of arms extending in opposite directions substantially transversely of said bolster arranged one pair adjacent each end of said bolster, a pair of torque rods mounted one on each of said transoms, means for providing universal joint connections between said bolster and the end of each of said arms adjacent said bolster, means for securing the other ends of said arms extending from opposite ends of said bolster on one side thereof to one of said torque rods with one arm secured to said rod adjacent each end thereof for pivotal movement about an axis extending substantially transversely of said rod, said connecting means for at least one of said arms adjacent each end of said bolster being constructed to provide for relative movement between said bolster and said arm, and means for connecting the other ends of said arms extending from opposite ends of said bolster on the other side thereof to the other one of said torque rods with one arm secured to said other rod adjacent each end thereof for pivotal movement about an axis extending substantially transversely of said other rod.

6. A vehicle truck having a frame including side frames and a pair of transoms extending therebetween, a bolster arranged between said

transoms, means for supporting said bolster on said truck frame, a tilting restraint device including pairs of arms extending in opposite directions substantially transversely of said bolster arranged one pair adjacent each end of said bolster, a torque rod mounted on one of said transoms, means for providing universal joints between said bolster and the end of each of said arms adjacent said bolster, at least one of said universal joints at each end of said bolster being constructed to provide for relative movement transversely of said bolster to provide for a change in distance between the outer ends of each pair of arms secured to the same end of said bolster, means for connecting the other ends of said arms extending from opposite ends of said bolster on one side thereof to said torque rod with one arm secured to said rod adjacent each end thereof for pivotal movement about an axis extending transversely of said rod, and means for securing the other ends of said arms extending from opposite ends of said bolster on the other side thereof to said frame for universal movement with respect thereto.

7. A vehicle truck having a frame including side frames and a pair of transoms extending therebetween, a bolster arranged between said transoms, means including a pneumatic cushion for supporting said bolster on said truck frame and for providing a lateral restraint thereto, a tilting restraint device including pairs of arms extending in opposite directions substantially transversely of said bolster arranged one pair adjacent each end of said bolster, a pair of torque rods mounted one on each of said transoms, means for providing pivotal connections between said bolster and the end of each of said arms adjacent said bolster, means for connecting the other ends of said arms extending from opposite ends of said bolster on one side thereof to one of said torque rods with one arm secured to said rod adjacent each end thereof for pivotal movement about an axis extending substantially transversely of said rod, said connecting means for at least one of said arms adjacent each end of said bolster being constructed to provide for relative movement between said bolster and said arm, and means for connecting the other ends of said arms extending from opposite ends of said bolster on the other side thereof to the other one of said torque rods with one arm secured to said other rod adjacent each end thereof for pivotal movement about an axis extending substantially transversely of said other rod.

8. A tilting restraint device for a laterally movable railway truck bolster arranged to be supported on a truck frame including a torque rod mounted on the truck frame, a pair of arms arranged one adjacent each end of the bolster, means for providing a universal joint connection between one end of each of said arms and the bolster, said connecting means for at least one of said arms adjacent each end of the bolster being constructed to provide for relative movement longitudinally of said arm between the bolster and said arm, and means for connecting the other end of each of said arms to said torque rod with one arm arranged adjacent each end of said rod for pivotal movement about an axis extending transversely of said rod at an angle tending to provide a tilting lateral pendulum motion to said bolster about a predetermined center.

ROBERT G. ANDERSON.
